UNITED STATES PATENT OFFICE.

FRANZ FRÖHLICH, OF LEIPZIG-SCHLEUSSIG, GERMANY.

BOBBIN FOR KNITTING MACHINES.

Application filed May 6, 1926, Serial No. 107,130, and in Austria January 23, 1926.

This invention relates to a bobbin for use in knitting machines and the like and of the kind provided with means for relieving the tension of the yarn after the winding.

The object of the invention is to construct the bobbin so that the yarn can be withdrawn from the same without entanglement of individual coils and with a minimum amount of resistance, and the invention consists essentially in forming a bobbin having a cylindrical upper portion and a conical, stepped lower portion, with longitudinal grooves and with expanding members arranged in said grooves so that they can be withdrawn for relieving the tension of the yarn.

Another feature of the invention consists in employing in connection with expanding elements in the form of withdrawable bars arranged in longitudinal grooves, a spreader by the removal of which the bars can be relieved of pressure and withdrawn without disturbing the yarn coils relative to one another.

Fig. 1 of the accompanying drawings represents a side view of the improved bobbin, partly in section, and

Fig. 2, a plan of the same without the spreader and with two of the expanding members withdrawn.

The bobbin is formed with an upper cylindrical portion *a* and a conical stepped portion *c*. It has a central bore *d* for the reception of the winding spindle and longitudinal grooves *e* for the reception of bars *f* whereby the bobbin is expanded previous to the winding.

The bars *f* extend beyond the normal circumference of the bobbin and support the yarn as the latter is wound on the same. When the cop is finished and after it has been removed from the spindle, the bars *f* are pushed down and withdrawn from beneath so as to relieve the tension of the yarn and allow it to retain its original elasticity. Fig. 2 shows two of the bars withdrawn and the ensuing contraction of the cop.

To facilitate the withdrawal of the bars and prevent the yarn windings from being disturbed in relation to one another, a

spreader is provided in the form of a grooved disc *g* which is inserted between the upper ends of the bars so as to prevent them from bearing against the bottoms of the grooves *e*. This spreading disc is withdrawn at the completion of the cop so as to enable the bars to recede and as they are thus relieved of pressure, to be easily withdrawn from the bobbin.

The stepping of the conical portion *c* enables the yarn to be pulled off easily in the axial direction of the bobbin without entanglement of the yarn windings. To prevent the coils on the cylindrical portion *a* from being entangled after the yarn tension has been relieved, this portion is covered with fabric, rubber or other frictional material. The rubber covering *b* clamps the bars *f* to the spreader *g* and holds both in position on the bobbin. It also retains the bars while the spreader is being removed.

I claim:

1. A yarn bobbin of the character described having a cylindrical upper and a stepped lower portion as well as a series of longitudinal grooves and expanding members arranged in said grooves so that they can be withdrawn for relieving the tension of the yarn after the winding.

2. The bobbin claimed in claim 1 and a withdrawable spreader for said expanding members whereby the pressure on the latter can be relieved to facilitate their withdrawal.

3. A yarn bobbin of the character described having a cylindrical upper and a stepped lower portion as well as a series of longitudinal grooves, expanding members arranged in said grooves so that they can be withdrawn for relieving the tension of the yarn after the winding, a withdrawable spreader for said expanding members whereby the pressure on the latter can be relieved to facilitate their withdrawal, and an elastic covering on the cylindrical portion adapted to clamp the expanding members to the spreader and hold both in position on the bobbin.

FRANZ FRÖHLICH.
